DISPENSING CAP FOR PRESSURIZED CONTAINERS

Philip H. Sagarin, Bridgeport, Conn., assignor to VCA Incorporated, Bridgeport, Conn., a corporation of Connecticut

Filed July 3, 1961, Ser. No. 65,799

Term of patent 14 years

(Cl. D58—26)

Fig. 1

Fig. 2

Fig. 3

Fig. 5

Fig. 4

Fig. 6

FIGURE 1 is a front elevational view of a dispensing cap for pressurized containers, showing my new design; FIG. 2 is a right side elevational view thereof;

FIG. 3 is a rear elevational view thereof;

FIG. 4 is a top plan view thereof;

FIG. 5 is a front perspective view taken from the top and left thereof; and

FIG. 6 is a bottom plan view thereof.

The characteristic feature of my design resides in the radial V-shaped finger notch in the top of the cap.

The dominant features of my design reside in portions shown in full lines.

I claim:

The ornamental design for a dispensing cap for pressurized containers, as shown and described.
